SET OF CHESSMEN

Howard Bruce Hunter, 4426 Harvey, Mesquite, Tex.

Substituted for abandoned design application Ser. No. 46,010, May 3, 1957. This application Jan. 11, 1960, Ser. No. 59,028

Term of patent 14 years

(Cl. D34—5)

Figures 1, 2, 3, 4, 5, and 6 are front elevational views of the Pawn, Castle, Knight, Bishop, Queen, and King, respectively, in a set of chessmen showing my new design.

Figures 7, 8, 9, 10, 11, and 12 are top plan views of the Pawn, Castle, Knight, Bishop, Queen, and King, respectively.

Figures 13, 14, 15, and 16 are side elevational views of the left side of the Knight, Bishop, Queen, and King, respectively.

This application is a substitute for my prior application D. 46,010 filed May 3, 1957, which is now abandoned.

I claim:

The ornamental design for a set of chessmen, as shown and described.
